ADDING MACHINE

Louis A. Culver and Jesse T. Barrow,
Houston, Tex.

Application May 13, 1933, Serial No. 670,873

1. Claim. (Cl. 235—74)

This invention relates to an adding machine. An object of the invention is to provide an adding machine of the character described which may be easily operated and whereby the total of 5 added amounts may be readily ascertained.

Another object of the invention is to provide an adding machine of such construction that it may be made of light material, may be easily operated and may be made of various sizes suitable for use for keeping scores of games, and the like, as well as for the addition of numbers generally.

With the above and other objects in view this invention has particular relation to certain novel features of construction, operation and arrangement of parts, an example of which is given in this specification and illustrated in the accompanying drawing, wherein:—

Figure 1 shows an elevational view showing the 20 front side of the adding machine.

Figure 2 shows an elevational view with the cover removed to display the interior mechanism.

Figure 3 shows a longitudinal sectional view 25 taken on the line 3—3 of Figure 1, and

Figure 4 shows a cross sectional view taken on the line 4—4 of Figure 1.

Referring now more particularly to the drawing wherein like numerals of reference designate the same parts in each of the figures the numeral 1 designates a box-like casing wherein the operating mechanism may be installed. The numeral 2 designates a removable cover for said casing. It is to be understood that the casing and cover may be made of any suitable material, and may be of any approved design.

The operating mechanism comprises a plurality of approximately similar units. These units have the supporting plates 3 to 7 inclusive arranged diagonally in the casing, as shown in Figure 3, and overlapping from left to right, as shown. Each plate has a facing of suitable tough, durable, material, glued or otherwise secured thereto and designated, respectively, by the numerals 8 to 12.

On the respective supporting plates, the discs 13, 14, 15, 16 and 17 are mounted to rotate, and these discs are provided with the marginal teeth 18, each disc having twenty of such teeth. There are the spring pawls 19 whose free ends are engageable with the teeth of the respective discs, said pawls having their other ends suitably anchored in place. These pawls permit the discs to revolve in a one way direction only and pre-

vent the discs from turning except when pressure is applied to turn the same.

The discs are mounted to turn on the pintles 20 through the respective supporting plates and face plates and the face plates may have extensions 21 which overlie the discs of adjacent units and have bearings to receive the outer ends of the corresponding pintles whereby said pintles are more securely retained in proper positions.

Each unit also has a counter disc mounted to rotate, said counter discs being indicated by the numerals 22, 23, 24, 25 and 26.

The outer face of each counter disc has all the numerals from 1 to 0 thereon which are successively visible, through the top openings 27, 28, 29, 30 and 31, as the discs rotate.

Secured to the undersides of the counter discs are the gears 32, 33, 34, 35 and 36 respectively having half the number of gear teeth as that of the corresponding discs 13 to 17 respectively, that is, each gear 32 to 36 inclusive has ten gear teeth which are in mesh with the gear teeth 18 of the corresponding discs 13 to 17 inclusive so that as one of the discs 13 to 17 is rotated the corresponding gears 32 to 36 inclusive will also be rotated to carry the numerals on the rotated counter disc successively in front of the corresponding openings 27 to 31.

The top 2 has a plurality of similar arcuate slots 37 to 41, inclusive, aligned above the teeth 18 of the corresponding discs 13 to 17. These slots are of sufficient length to expose one half of the teeth of these discs. Any one of the series of discs 13 to 17 may be rotated by inserting a pencil or other suitable implement through the corresponding slot in engagement with one of the teeth 18. As shown, said discs should be rotated to the right. The spaces between the teeth 18 are indicated on the top 2 by the numerals 1 to 9 inclusive and the gearing is such that when the rotating implement is inserted opposite any particular number and the corresponding disc turned to the right as far as the corresponding slot will permit, the corresponding numeral on the corresponding counter disc will be brought opposite the corresponding opening of the series of openings 27 to 31. The discs 22, 23, 24 and 25 have the projecting teeth 42, 43, 44, and 45, respectively arranged to engage the teeth 18 of the discs 14, 15, 16 and 17.

Consequently a complete rotation of any particular counter disc will cause a partial rotation of the next succeeding disc to the left, of the series of discs 14 to 17—for example upon a complete 50 rotation of the disc 22, the disc 23 will be rotated 45 through an angle of 18°, the disc 24 through an angle of 9°, and the disc 25 through an angle of 4.5°. The discs 22, 23, 24 and 25 are so arranged that when the disc 22 is rotated 55 through an angle of 18°, the disc 23 will be rotated through an angle of 9°, the disc 24 through an angle of 4.5°, and the disc 25 through an angle of 2.25°. The discs 13 to 17 are so arranged that when the disc 13 is rotated through an angle of 18°, the disc 14 will be rotated through an angle of 9°, the disc 15 through an angle of 4.5°, and the disc 16 through an angle of 2.25°.

rotation of the disc 22 the tooth 42 thereof will engage a tooth 18 of the disc 14 causing said disc 14 to turn one-twentieth of a complete rotation, which in turn causes the counter disc 23 to turn one tenth of a rotation, and so on.

Accordingly, a pencil or other operating implement may be inserted in either of the slots 37 to 41 and the corresponding disc given successive partial rotations depending upon the numbers to be added. If the sum of said numbers is less than ten, the total will be shown by the corresponding opening of the series of openings 27 to 31, but if the sum of the numbers to be added exceeds 9 the succeeding discs to the left will be intermittently rotated as hereinabove explained so that the sum of the numbers will be shown through the corresponding openings:—

To illustrate, if it be desired to add 1, 3 and 5, a pencil may be inserted in slot 37 opposite 1, and the disc rotated as far as the slot will permit, and then the pencil, or other implement, may be inserted in said slot 37 opposite 3 and the disc rotated again as far as said slot will permit and the pencil then inserted through the slot opposite 5 and the disc turned, as before, and thereupon the numeral 9 of the counter disc 22 will appear through the opening 27. If the sum of the numbers to be thus totaled equals, or exceeds, ten, the disc 22 will perform more than a complete rotation and the disc 14 will be partly rotated so as to carry the proper number on the counter disc 23 opposite the opening 28 and the unit and tens numbers will thus be rendered visible through the openings 27 and 28; and the operation may be continued as far as desired within the capacity of the machine. The machine shown will show totals of five figures but it is obvious that a machine of greater or

less capacity may be constructed utilizing the same principle.

The drawing and description disclose what is now considered to be a preferred form of the invention by way of illustration only, while the broad principle of the invention will be defined by the appended claim.

What we claim is:—

A machine for registering totals comprising a casing having openings therein, separate independent units in the casing forming a series of rotatable transmitting members exposed for manual operation, and a series of rotatable number carriers each carrier being associated with and geared to each transmitting member, the corresponding carrier having a series of numerals thereon arranged to be successively exposed through the corresponding openings, as the carriers are rotated, means operative, upon a complete rotation of a carrier, to impart a partial rotation to the next succeeding transmitting member, said casing having series of numerals thereon, corresponding to and arranged in the same sequence as the numerals on the corresponding carriers, said casing numeral being arranged to indicate the required amount of rotation of a transmitting member to produce a selected numeral opposite the corresponding opening overlapping plates in the casing, an extension on each plate, except one, the extension of each plate overlying the transmitting member of an adjacent plate and pintles through the extensions and through the corresponding transmitting members and plates and forming means on which the transmitting members rotate.
